C. MATTHEWS.

Smoking Tube.

No 2,1973.

Patented Nov. 2, 1858.

UNITED STATES PATENT OFFICE.

CHARLES MATHEWS, OF NEW YORK, N. Y.

SMOKING-TUBE.

Specification forming part of Letters Patent No. 21,973, dated November 2, 1858.

To all whom it may concern:

Be it known that I, CHARLES MATHEWS, of the city, county, and State of New York, have invented a new and useful Compound Smoking-Tube for Smoking Tobacco or other Substances in a Finely-Divided State; and I do hereby declare that the following is a full, clear, and exact description of the same, reference being had to the accompanying drawings, forming part of this specification, in which—

Figure 1 represents an elevation of my compound smoking-tube ready for smoking. Fig. 2 is a longitudinal central section of the same. Fig. 3 is an elevation of the inner or containing tube. Fig. 4 is an elevation of the outer or draft tube. Fig. 5 is an elevation of the mouth-piece. Fig. 6 is a plan or top view of a piece of paper used in closing up one end of the inner or containing tube. Fig. 7 is a plan or top view of my ash-pan. Fig. 8 is a perspective view of the same.

Similar letters of reference indicate like parts in all the figures.

This invention consists in arranging two tubes one inside the other, the outer tube to be provided with a mouth-piece, which consists of a short tube of thick and firm paper or pasteboard, and the inner tube, which contains the tobacco or other substance to be smoked in a finely-divided state, to be closed at the upper end in a peculiar manner, and to fit loosely into the outer tube, so as to leave a sufficient space for the smoke to pass between the tubes up to the mouth-piece.

The invention further consists in arranging an ash-pan in such a manner that it slides on the compound smoking-tube by means of a loop, and which is so constructed that the ashes dropping off from the lighted end of the tube are deposited in the ash-pan without inconvenience to the smoker.

To enable others to fully understand and construct my invention, I will proceed to describe the same.

The compound smoking-tube A is shown in Fig. 1 ready for smoking. B is the ash-pan, which slides on the tube. The construction of the tube is shown in Fig. 2, and detail views of its several parts are shown in the other figures.

C is the outer or draft tube, constructed out of thin paper, and D is the mouth-piece, which

fits into the upper end of the draft-tube C, and is constructed of thick and firm paper or pasteboard, being about one and three-fourths or two inches long. The mouth-piece fits closely into the draft-tube, so as to leave no other passage for the smoke but through the central opening of the same.

E is the inner or containing tube, constructed also of thin paper, and fitting loosely into the draft-tube C, so as to leave a passage for the smoke between the two tubes, as shown in Fig. 2. The upper end of this tube E is closed up by a piece of paper, F, a plan or top view of which is shown at Fig. 6. The shape of this paper is such that the end of the tube is chamfered off on two sides, so that when the tube E is placed within the draft-tube C the upper end of the same does not cover up entirely the central opening of the mouth-piece. By this arrangement the draft is considerably facilitated.

It must be remarked that the inner tube, E, is of such a length that the same, when inserted into the draft-tube C, with its closed end forward, sliding into the same until stopped by the inner end of the mouth-piece, projects with its open end a little beyond the draft-tube. The inner tube, E, is now charged with finely-cut tobacco or other substance in a finely-divided state, the end of the tube is twisted, as shown in Fig. 1, and the compound smoking-tube is then ready for consumption. When lighted, the ashes from the tubes drop off very readily, and in order to overcome a great inconvenience arising from this source I have constructed an ash-pan. This is shown in Fig. 1 as applied to the compound smoking-tube, and also shown detached in Figs. 7 and 8. The ash-pan consists of a cup, G, rather wider than the diameter of the compound tube, and a loop, H, is attached to the cup, of such a size that it slides readily on the tube A. When applied to the tube, the ashes dropping from the lighted end of the same are deposited in the cup G; and it will be understood that it is necessary as the tube is consumed to bring the loop H nearer to the mouth-piece, which latter is at the same time protected by the loop from being burned.

Having thus described my invention, what I claim as new, and desire to secure by Letters Patent, is—

1. Arranging the tubes C and E with the mouth-piece D in such relation to each other that they form a compound smoking-tube for

smoking tobacco or other substance in a finely-divided state, the whole being constructed and arranged as specified. 2. Closing the upper end of the tube E in such a manner that the same, when inserted into the draft-tube C and brought close up to the inner end of the mouth-piece D, leaves a sufficient space for the passage of the smoke up through the central opening of the mouth-piece, as described.

3. Constructing an ash-pan in such a manner that the same slides on the compound smoking-tube by means of a loop, H, so that the ashes dropping from the lighted end of the tube are deposited in the ash-pan, substantially as specified.

CHARLES MATHEWS.
